UNITED STATES PATENT OFFICE

JOSEPH M. WARTOW, OF BOSTON, MASSACHUSETTS

DESIGN FOR A TRANSPARENT ADVERTISING SIGN HOLDER

Application filed March 20, 1933. Serial No. 47,533. Term of patent 3½ years.

To all whom it may concern:

Be it known that I, JOSEPH M. WARTOW, a citizen of the United States residing at Boston, in the county of Suffolk and State of Massachusetts, have invented a new, original, and ornamental Design for a Transparent Advertising Sign Holder, of which the following is a specification, reference being had to the accompanying drawing, forming part thereof.

The figure is a perspective view of a transparent advertising sign holder, showing my new design.

I claim:

The ornamental design for a transparent advertising sign holder, as shown.

JOSEPH M. WARTOW.
